UNITED STATES PATENT OFFICE

2,225,314

MASTER PLATE FOR KEY PUNCHES

Lucien L. McCart, Forest Hills, N. Y., assignor, by
mesne assignments, to The McBee Company,
Athens, Ohio

Application November 29, 1939, Serial No. 306,603

3 Claims. (Cl. 164—111)

My invention relates to that type of devices illustrated and described in my United States Letters Patent No. 2,144,412, issued January 17, 1939, which describes a machine for slotting cards in order that they may be sorted into a numerical or other desired sequence as taught by United States Letters Patent No. 1,544,172, issued to Alfred Perkins. This patent shows a stack of cards, each of which is provided with a series of 5 perforations adjacent one or more edges of the card. These perforations are located so that each one can have the material intermediate the perforations and the edge of the card cut away forming a notch or slot. These notches are arranged to form a pattern which will designate a particular desired classification. By passing a sorting device through the perforations in a mixed stack of cards and lifting it, the cards which do not have slots or notches will be carried upward by the sorting rod or device and by placing 10 these cards at the back of the stack and repeating the operation the cards will be sorted into a numerical sequence in a very short time. This is fully set forth and described in the said Perkins patent to which reference may be had for a full 15 and complete description of the device in all its details. In my Patent No. 2,144,412 hereinbefore referred to, I describe a master card or key plate which has a pattern of notches or slots cut in one 20 of its edges so that only certain of the punches may be operated thereby causing the remaining 25 punches to notch or slot the desired pattern in the card which is to be slotted. When the master card or plate having the desired pattern is 30 placed in the machine, one or more of the devices constructed according to the Perkins patents are 35 inserted in the machine and on operation of the punches, the pattern of slots appearing on the master card will be reproduced on the Perkins 40 card.

In order to insure the correct pattern of notches being punched in the card, the key plate must always be in the correct position. It is common practice for companies to issue credit 45 cards to their customers as a means of identification and the clerk makes a record of the transaction by copying in longhand the name and address and account numbers, but the handwriting is not always legible and frequently employees 50 make errors in the spelling of the names or copying of the addresses.

My invention has for its object to provide a master card having, not only the openings adapted to register with one or more die slots, but 55 also the perforations called for by the Perkins

patent so that a pattern of slots or notches designating this account number may be formed in the card. This card is supplied to the customer whom on making a purchase, hands it to the clerk. The clerk instead of having to laboriously copy the name and address, simply inserts the card in a punching device, such as is described in my patent, or a similar machine, this key plate or master card will render inactive all 10 of the punches except those which would slot the pattern of notches designating the particular account number of that particular customer. The clerk would then insert a sales slip and charge card, or either of them, and on the device being operated the sales slip and charge card, or either 15 one, as the case may be, will be slotted with the pattern of slots or notches which identify that particular account number. This eliminates the element of error and by sorting as described in the Perkins patent, posting of the account to the 20 right customer is insured.

A further object is to provide means which will automatically insure the master card or key plate always being in the correct position and prevent the punches being inserted in the master card 25 upside down.

My means of accomplishing the foregoing objects may be more fully comprehended by having reference to the accompanying drawings which are hereunto annexed and are a part of this 30 specification in which I have illustrated a master card embodying my invention:

Fig. 1 is a plan view of a master card;

Fig. 2 is a similar view with a pattern of slots or notches referring to a single classification as 35 illustrated, it is number 1226, which is the account number of the customer in question;

Fig. 3 is a view of the master card in a machine;

Fig. 4 is a sectional view on line 4—4 in Fig. 3. 40 Similar reference numerals refer to similar parts throughout the specification.

As shown in the drawings, the plate or master card 1 is provided with a plurality of openings 2 adapted to register with one or more of the die 45 slots in the die block of a slotting machine. It should be understood that the location and numbers of these openings will be determined by the pattern of notches to be cut in the sales slip or charge card. Adjacent the other edges of the 50 plate 1 form perforations 3 which are so disposed adjacent one or more edges of the plate or card 1 that one can cut away the intervening material 4 on each as shown by dotted lines 5 in Fig. 1 thus forming a slot 6 in Fig. 2. By slotting 55

a pattern of these notches as described in the 5 Perkins patent it is possible to sort the master cards and obtain all of the cards of this account number, as illustrated it is 1226, which are in the mixed pack of sales slips and statistical cards, or either of them, which are turned in by the clerk or station, without a chance of a mistake. On the edge 1 of the card 1 are formed slots 2 through which the punches are operated in order 10 for the machine to punch the desired pattern in the card sales or charge slip (not shown).

As shown in Fig. 4 I cast or form an abutment 18 adjacent an end of the die plate 8. As illustrated only one is shown. Additional ones may 15 be located on the die plate if desired. The important point is that, when the master card 1 is inserted in the punching machine, unless it is positioned so that the edges of a cut away portion 11 will contact the abutment 18, the operator will 20 at once perceive that the card is incorrectly positioned because it will not enter fully into its proper place.

It will be apparent that no particular shape or 25 location for the abutments is necessary, provided they are so arranged that they will prevent the inadvertent insertion of the master card to the incorrect position. It is obvious that should the clerk reverse the master card 1 and attempt to 30 insert it in the punching machine 8 that it would strike the abutment thus causing the clerk to perceive his error and the machine would not be operated. In this way, I avoid the chance of an

error occurring in the identification of the particular account. Obviously, each master card or key plate has a different combination of notches in the edge 1 to correspond to the pattern it is desired to have notched by the punches. 5

Having described my invention, what I regard as new and desire to secure by Letters Patent is:

1. A master and sorting card for rendering inoperative certain punches, having a pattern of slots in one edge to designate a single classification, there being a plurality of perforations adjacent one or more edges of said card adapted to be notched out to the edge and means on said card, adapted to indicate the position thereof. 10

2. A master and sorting card for rendering inoperative certain punches, having a pattern of slots in one edge to designate a single classification, there being a plurality of perforations adjacent one or more edges of said card adapted to be notched out to the edge, and a portion of said 15 card being cut away to engage an abutment on a punching machine.

3. A master and sorting card for rendering inoperative certain punches having one or more 20 slots in one edge through which one or more punches may operate to form a predetermined pattern, there being a plurality of perforations adjacent one or more edges of said card adapted to be notched out to the edge, and means on said 25 card adapted to indicate the position thereof. 30
